METHOD OF BOTTOM-FILLING SHOES AND THE LIKE.

1,283,234.

Specification of Letters Patent. Patented Oct. 29, 1918.

Application filed September 29, 1917. Serial No. 193,942.

To all whom it may concern:

Be it known that we, ERNEST E. LIBBY and EDWARD F. LOGAN, citizens of the United States, residing at Lynn, in the county of 5 Essex and State of Massachusetts, have invented certain new and useful Improvements in Methods of Bottom-Filling Shoes and the like, of which the following is a specification.

10 Our invention relates to a new method of bottom filling boots and shoes, whereby, in some instances, the process of shoe manufacturing is considerably simplified and certain operations hitherto deemed necessary are 15 avoided. Furthermore, greater ease and certainty of manipulation are brought about and a much improved product is obtained.

While our new process of bottom filling may be applied with success to all systems 20 of shoe manufacturing, except "turns" and "stitch downs", it is particularly applicable to boots and shoes made by the "klench" or "staple" welt system and we shall describe our process with particular reference to this 25 system.

Under the present method of making boots and shoes, by the "klench" or "staple" welt system, after the shoe upper has been lasted to the insole by temporary or permanent fasteners, such as lasting tacks, the last is removed. During the operation of removing 30 the last, the shape of the shoe is generally distorted. The insole, no longer having the substantial support of the last, twists at the 35 shank portion thereof, and the forepart curls and twists out of shape, often leaving the unfinished boot or shoe in an unfit condition to proceed with the next operation. Furthermore, the longer the unfinished shoe remains on the shoe rack, without the support 40 of the last, awaiting the attaching of the welt, the more aggravated does this condition become. If the welt is then attached while the shoe is out of shape, the staples, or 45 whatever means are used to hold the welt in place, so secure the bottom that it can not be easily forced back into shape again. In many cases the distortion of the boot or shoe is so bad that, if its manufacture is continued, the result is an imperfect product 50 unusable as a first class article.

Some manufacturers have tried to remedy these defects by relasting one or more times, by applying pressure with a leveling ma-

chine and even by hammering and pounding. 55 In any case much inconvenience and delay is experienced and an inferior product is produced. In many cases manufacturers have been compelled to discontinue manufacturing by this process on account of the 60 extra expense and loss of time to which they have been put trying to remove these defects and to make the product more or less marketable.

By our process the above described disadvantages are avoided and at the same time the bottom of the boot or shoe is filled permanently and inexpensively. In practising our invention, after the upper has been lasted to the insole, we attach to the insole 70 by any secure means, while the partially constructed shoe is still in the shape desired, and preferably before the last is removed, a comparatively firm filler consisting of one or more layers of a suitable material, sufficiently stiff to hold the shoe in shape during the remaining operations of manufacture. 75

While it is essential that this filler extend from the toe or near the toe, to the heel, or near the heel of the boot or shoe in an unbroken piece, it is not essential that all layers should be unbroken when more than one layer is used. If the manufacturer chooses, he may first put a forepart filler in the boot or shoe bottom and then place a long filler 80 over this, such long filler running in an unbroken piece from the toe or near the toe to the heel or near the heel, or he may first put in a forepart filler and a shank piece and then the long filler, or he may first place the 85 long filler in the boot or shoe bottom and than a forepart filler or a forepart filler and a shank piece over it, or he may use two or more long fillers with or without a shank piece. In fact the manufacturer 90 may use any combination of filler material he desires, the essential part being that there must be at least one unbroken layer or filler material running from the toe or near the toe to the heel or near the heel of 95 the boot or shoe. 100

The material, when placed in the boot or shoe as we have described, serves not only as a means of holding the shoe in shape during the process of manufacture, but also as 105 a permanent bottom filler which continues to hold the boot or shoe in shape during its wearing life; and further, when used in con-

nnection with the "klench" or "staple" welt system, serves as a guide for attaching the welt uniformly and in its proper position. Various materials may be employed to serve as fillers as described, provided the same are firm or stiff enough to give the insole of the lasted shoe upper and insole the necessary firmness and rigidity to withstand the succeeding operations.

10 Referring to the drawing, wherein we have illustrated one form of our invention,

Figure 1 shows in plan view the bottom portion of the lasted shoe upper and insole with the inner layer of the filler and its corresponding shank piece in place;

Fig. 2 shows in plan view the bottom portion of the lasted shoe upper and insole with the inner layer of the filler and its corresponding shank piece covered up by the outer layer of the filler which holds the shoe in shape and at the same time serves as a guide for the welt which is here shown partially attached; and

Fig. 3 shows in cross-section a completed shoe bottom filled by the method of our invention.

Referring to the drawing, 1 represents an insole of the usual sort attached by the usual lasting method to the upper 3 by the lasting tacks 7. After the sole and upper have been lasted together, and either before or after, though preferably before, the last has been removed, the comparatively stiff filler F is attached securely to the outer face of the insole. This filler consists of two layers or sections, first an inner layer or section 6 generally of a thickness corresponding with the thickness of that portion of the upper which overlaps the insole, and the other and outer layer or section 9 generally of a thickness corresponding with the thickness of the welt to be applied. Since the section 6 is generally shaped so as to fill only the toe portion of the shoe, it is customary to fill the shank portion with the shank piece 4 as shown in the drawing, and the heel piece 4'. Preferably the parts 6, 4 and 4' are integral as illustrated. Since, as a result of the lasting process, the space defined by the inner edge of the over-lapping portion of the upper is irregular, the shape of the inner layer or section 6 of our filler member need not be very accurately predetermined. For the outer edge of the outer layer 9 of the filler member may be so shaped that it will define the line along which it is desired that the welt be attached. The outer edge of this filler member 9 will then serve as a guide for the inner edge of the welt in the attachment of the same to the lasted shoe upper. Where

the filler sections 6 and 9 are of the same material it is obvious that the same may, if desired, be made integral.

After the combined filler members 6 and 9, of suitable material, have been attached to the insole by any desirable fastening means such as the tacks 11, the welt 2 is attached to the lasted shoe upper and insole by means of the staples 8, the outer projecting edge of the filler member 9 serving as a guide for the inner edge of the welt while being attached. The welt is attached from one side of the lasted shoe upper and insole at the breast of the heel all the way around the shoe to the corresponding point of the breast of the heel on the other side of the shoe. As a result of the previous attachment of the reinforcing filler members 6 and 9, the lasted shoe upper and insole keep their shape firmly and rigidly during the entire Weltung process and the distortion referred to above is entirely avoided. After the welt has been attached by staples, stitching or other means, the outer sole 10 is attached to the shoe, the filler members 6 and 9 being left permanently in the shoe to serve as filler means.

It is clear from the above description that the use of a long filler of a sufficiently firm material, running from the toe to the heel of the boot or shoe, which holds the boot or shoe in shape during the process of manufacture as well as after it is made and which serves as a permanent bottom filler, and, when necessary, as a guide for the application of the welt, considerably simplifies the process of manufacture and results in a superior product. The use of this type of filler, especially when such fillers are made of the material referred to in our co-pending application, results in a further improvement of the product due to the superior properties of fillers made of such material.

What we claim is:

1. A method of bottom filling welt shoes and the like, comprising the step of applying a comparatively stiff, permanent bottom filler to the outer face of the insole in contact with said insole before the welt is attached.

2. A method of bottom filling welt shoes and the like, comprising the step of applying a permanent, shape retaining material to the outer face of the insole in contact with said insole of a lasted upper and insole before the welt is attached.

3. A method of bottom filling welt shoes and the like, comprising the step of applying a permanent bottom filler of comparatively stiff material to the outer face of the insole in contact with said insole before the welt is attached or the last removed.

4. A method of bottom filling welt shoes and the like, comprising the step of applying a permanent bottom filler of comparatively stiff material to the outer face of the

- insole in contact with said insole before the welt is attached, the edge of the outer face of the filler conforming to the contour to be assumed by the welt,
- 5 5. A method of bottom filling shoes and the like, comprising the steps of lasting the shoe upper to the insole, applying a permanent bottom filler of comparatively stiff material to the outer face of the insole in contact with said insole of the lasted shoe upper and insole, the outer edge of the outer face of the filler conforming to the contour to be assumed by the welt, and thereafter attaching the welt while causing the same to be guided by the edge of the outer face of the filler.
- 10 6. A method of bottom filling shoes and the like, comprising the steps of lasting the shoe upper to the insole, applying a permanent, comparatively stiff material to the outer face of the insole in contact with said insole, the outer edge of the outer face of the said material conforming to the contour to be assumed by the welt, attaching the welt while causing the same to be guided by the edge of the outer face of the filler, and thereafter completing the shoe without removing the said material.
- 15 7. A method of bottom filling shoes and the like comprising the steps of applying a suitably shaped permanent bottom filler of comparatively stiff material to the outer
- face of the insole in contact with said insole, and thereafter attaching the welt while causing the same to be guided by the edge of the outer face of the filler.
- 16 8. A method of bottom filling shoes and the like which comprises the steps of applying a permanent templet of comparatively stiff material to the outer face of the insole in contact with said insole, said templet serving as a guide for applying the welt, as a shape retaining device during the operations of manufacture, and as a filler for the shoe.
- 17 9. A method of preventing undue distortion of a welt shoe or the like during its manufacture which consists in applying a piece of comparatively stiff material to the outer face of the insole in contact with said insole before the welt is applied and retaining it after the shoe is completed.
- 20 10. A method of bottom filling welt shoes and the like which comprises the steps of applying a permanent bottom filler to the outer face of the insole before the welt is attached, and attaching the welt so that said filler abuts the same substantially throughout their adjacent edges.
- 25 In testimony whereof we affix our signatures.
